(57) **CLAIM**

The ornamental design for a HDMI dongle apparatus, as shown and described.

DESCRIPTION

FIG. 1 is a front perspective of the HDMI dongle apparatus according to one embodiment.

FIG. 2 is a top view of the HDMI dongle apparatus according to one embodiment.

FIG. 3 is a bottom view of the HDMI dongle apparatus according to one embodiment.

FIG. 4 is a front view of the HDMI dongle apparatus according to one embodiment.

FIG. 5 is a rear view of the HDMI dongle apparatus according to one embodiment.

FIG. 6 is a left side view of the HDMI dongle apparatus according to one embodiment; and,

FIG. 7 is a right side view of the HDMI dongle apparatus according to one embodiment.

The broken lines shown in the drawings represent portions of the HDMI dongle apparatus that form no part of the claimed design.
